United States Patent

Des. 240,549
Patented July 13, 1976

240,549

LIGHTING FIXTURE

Zia Eftekhar, Glendale, Calif., assignor to Lightolier Incorporated, Jersey City, N.J.

Filed June 20, 1975, Ser. No. 588,803

Term of patent 14 years

Int. Cl. D26—05

U.S. Cl. D48—23 R

FIG. 1 is a perspective view of a lighting fixture showing my new design.

FIG. 2 is an end view thereof;

FIG. 3 is a side elevational view thereof;

FIG. 4 is a top plan view, and

FIG. 5 is a bottom plan view.

The lighting fixture is stippled to indicate contrast.

I claim:

The ornamental design for a lighting fixture, substantially as shown and described.
